(57) **CLAIM**

The ornamental design for a collapsible container, as shown and described.

DESCRIPTION

FIG. 1 is a perspective view of a first embodiment of a collapsible container showing my new design;

FIG. 2 is a front elevation view thereof;

FIG. 3 is a left side view, with the right side view being a mirror image thereof;

FIG. 4 is a top plan view thereof;

FIG. 5 is a bottom view thereof;

FIG. 6 is a perspective view of a second embodiment of a collapsible container showing my design;

FIG. 7 is a front elevation view thereof;

FIG. 8 is a left side view, with the right side being a mirror image thereof;

FIG. 9 is a top plan view thereof; and,

FIG. 10 is a bottom view thereof.
